DESIGN FOR A SELF-SERVICE DISPLAY CASE

Cyrus F. Hoffman, Trenton, N. J., assignor to C. V. Hill & Company, Inc., Trenton, N. J., a corporation of New Jersey

Application October 5, 1945, Serial No. 122,544

Term of patent 14 years

(Cl. D80—11)

To all whom it may concern:

Be it known that I, Cyrus F. Hoffman, a citizen of the United States, residing at Trenton, in the county of Mercer and State of New Jersey, have invented a new, original, and ornamental Design for a Self-Service Display Case, of which the following is a specification, reference being had to the accompanying drawing, forming a part thereof.

Fig. 1 is a perspective view of the display case embodying my design;

Fig. 2 is a side elevation of the display case embodying my design, and

Fig. 3 is a top plan view of the display case embodying my design.

I claim:

The ornamental design for a self-service display case, as shown.

CYRUS F. HOFFMAN.
